CLAIM

The ornamental design for a communicator, as shown and described.

DESCRIPTION

FIG. 1 is a bottom plan view of a communicator showing my new design;

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a perspective front view thereof;

FIG. 8 is a perspective rear view thereof;

FIG. 9 is a front view of the communicator of FIGS. 1-8 showing my new design in an in-use open position;

FIG. 10 is a perspective front view thereof;

FIG. 11 is a front view of the communicator of FIGS. 1-8 showing my new design in a second in-use open position; and, FIG. 12 is a perspective front view thereof.

The rectangular region on the upper half of the front of the communicator, shown in FIGS. 3 and 7, and the rectangular region on the inside of the communicator, shown in FIGS. 9-12, represent display screens.
